UNITED STATES PATENT OFFICE

2,620,004

PICKING BAG

Charles W. Heitmeyer, Cincinnati, Ohio

Application September 16, 1950, Serial No. 185,245

3 Claims. (Cl. 150—2)

1

This invention relates to picking bags, and it particularly pertains to picking bags for fruits and vegetables having a soft, flexible, compressible lining with a sidewall portion extending below the open bottom of the bag to provide a bottom closure for the bag when the fruits or vegetables are being picked and also provide a temporary lining or pad for the bottom of a container into which they are dumped from the picking bag.

Great care is necessary to prevent fruits and vegetables, such as apples, pears, plums, tomatoes, and the like from being bruised while being picked and transferred from the picking bags into baskets or other containers. To prevent this the bags are either made of rigid, non-flexible material or else provided with a rigid non-flexible protector in which a flexible container is placed. Such devices are of course not only heavy and cumbersome to handle but they do not provide means for protecting the contents from being bruised while contained in the bag or in being transferred from it to another container in which they are placed for shipment or for further handling.

Accordingly, the principal object of my invention is in the provision of a picking bag which is soft, flexible and compressible.

Another object of the invention is in the provision of a picking bag which protects the contents contained therein against bruising and while being removed therefrom.

Another object of the invention is in the provision of a picking bag which is of a construction to provide a common means for closing the bottom and in transferring the contents to another container.

Further objects, and objects relating to details of construction will readily appear from the detailed description to follow. In one instance, I have accomplished the objects of my invention by the device and means set forth in the following specification. My invention is clearly defined and pointed out in the appended claims. A bag structure constituting a preferred embodiment of my invention is illustrated in the accompanying drawings forming a part of this specification, in which:

Fig. 1 is a perspective view of a picking bag embodying my invention with the bottom end open.

Fig. 2 is a vertical cross sectional view of the bag on line 2—2 of Fig. 1.

Fig. 3 is a perspective view of the bag with the bottom end closed.

2

Fig. 4 is a detailed cross sectional view of the bottom end of the bag and a container in which the contents of the bag are being dumped.

The invention generally described comprises a flexible bag made from a sheet of any suitable material, such as canvas or similar fabric. The opposite ends of a sheet are joined together to provide a surrounding wall open at its top and bottom ends. A ring is attached to the upper end of the bag for holding it in open uncollapsed condition and also to receive shoulder straps or other holding means by which the bag is carried by the user. The bottom open end can be opened and closed by folding and fastening it to the side of the bag. The lining is of any suitable material, such as sponge rubber or the like. This liner is of the same general construction and shape as the flexible bag except that it has an extension projecting downwardly on one side. This projection of the liner may be folded with the bottom end of the bag to close the bottom end, and both are secured in folded position by means carried on one side wall to engage with means carried on the other side wall of the bag. When the bag is to be dumped or emptied, the hook is unfastened, thereby permitting the extension to be laid upon the bottom of a container into which the contents of the bag are to be dumped. Accordingly, with this construction the contents are not only protected against crushing and bruising while contained in the bag but also while they are being transferred from the bag into another container.

Referring specifically to the drawings, numeral 2 designates a bag of tubular form made of fabric and open at its top and bottom ends. The upper margin 3 of the bag is folded into a hem and stitched at 5 about a ring 6 that is contained therein for holding the open top end of the bag against collapsing. Links 8 are fastened to the top of the bag by straps 9, riveted at 10, for receiving the ends of shoulder straps A or other holding means. The opposite ends of the straps are detachably connected to another link 11 clipped to the opposite side of the top end of the bag by strap 12. A second link 11a is secured to the strap in a position to receive a hook 13, carried near the bottom end of the bag and on its opposite side, when the bottom end is folded and closed. Below this link 11a is another link 14 held by a strap 15 riveted at 16 to the bag. The closed bag can be made of smaller capacity when hook 13 is connected to the top link 11a and of larger capacity when connected to the lower link 14.

The bag is lined with soft flexible, compressible material of any suitable material, preferably sponge rubber. A sheet of sponge rubber 17 is fitted to the shape of the bag and secured thereto by having its upper end contained within the hem and held by the stitching 5. The bottom end of the lining is provided on one side with extension 20 that is of substantial length to provide a pad for covering the bottom of a basket or container 21, into which the bag contents 22 are dumped, for preventing them from being bruised in being dumped.

When the contents of the bag are to be dumped into a container 21 the hook 13 is disengaged from link 14 or 11a to open the bottom end of the bag. The bag is placed in the container so that the extension of the liner will lie across the bottom of the container, and as the bag is pulled away and withdrawn from the container the bag contents will be rolled over the extension as they are dumped from the bag. The extension serves as a cushioning pad to prevent the contents being bruised in being rolled off into the container.

From the foregoing description of the picking bag, its construction and use is obvious. While a flexible bag is preferred, it will be understood that the flexible and compressible lining is also adapted for use with bags formed of any material. Although the lining material is preferably of such material as sponge rubber, it could, of course, be of any material that is sufficiently soft and compressible to serve as a pad or cushion to protect the bag contents from being bruised and crushed. The extension on the lining not only serves as a pad protector for dumping the contents from the bag but it also serves in building up a bulky mass on the bag while it is used for picking, thereby further protecting the contents from being bruised.

I am aware that there may be various changes in the construction of the preferred embodiment herein illustrated and described without departing from the spirit of the invention, and, accordingly, my invention is limited only by the appended claims.

Having thus described my invention what I claim as new and useful and desire to secure by United States Letters Patent is:

1. A picking bag comprising a tubular body portion open at its opposite ends, a flexible and compressible lining having a portion extending beyond one of the open ends of the tubular body, at one side only of said tubular body, adapted to

be folded with the bottom end of the tubular body portion for closing the bottom end thereof and also to provide a cushion for the bottom of another container into which the contents are dumped from the picking bag, means attached to one side of the tubular body portion adjacent its bottom end back of the lining extension, and means on the opposite side of said tubular body portion remote from its bottom end adapted to be detachably connected with the first mentioned means for opening and closing the bottom end of the bag.

2. A picking bag comprising a combination of a tubular member opening at its opposite ends, a ring attached to the top end of the tubular member, a lining of sponge rubber for the tubular member having an extension projecting beyond the open bottom end opposite to that to which the ring is attached and at one side only, means for securing the lining to the bag, and means for detachably connecting the opposite sides of the tubular member above the extension for opening and closing the bag.

3. A picking bag comprising a flexible tubular body open at its opposite ends, a hem on one end of the body having a ring secured therein for holding said end open, a soft, compressible lining having an extension on one side projecting below the bottom open end of the body at one side only of said body, a plurality of fastening means vertically spaced apart on one side of the body, and cooperating fastening means carried on the other side of the body adapted to be selectively connected to any of the fastening means.

CHARLES W. HEITMEYER.
